No. 690,145.

Patented Dec. 31, 1901.

W. S. HAMM.

CAR ILLUMINATING APPARATUS.

(Application filed June 15, 1901.)

(No Model.)

UNITED STATES PATENT OFFICE.

WILLIAM S. HAMM, OF CHICAGO, ILLINOIS, ASSIGNOR TO THE ADAMS & WESTLAKE COMPANY, A CORPORATION OF ILLINOIS.

CAR-ILLUMINATING APPARATUS.

SPECIFICATION forming part of Letters Patent No. 690,145, dated December 31, 1901.

Application filed June 15, 1901. Serial No. 64,731. (No model.)

To all whom it may concern:

Be it known that I, WILLIAM S. HAMM, a citizen of the United States, and a resident of Chicago, county of Cook, and State of Illinois, 5 have invented certain new and useful Improvements in Car-Illuminating Apparatus, of which the following is a specification and which are illustrated in the accompanying drawings, forming a part thereof.

10 This invention relates to an illuminating apparatus which is particularly adapted for use in railway-cars, and has for one of its objects to provide a simple and effective illuminator designed to be substituted for the chandelier and other hanging or suspended lamps usually employed and which are objectionable owing to the space utilized thereby and the heat created by the same within the car.

15 A further object is to provide means combined with an illuminating apparatus to effect thorough ventilation of the car.

The invention comprises, in general terms, a longitudinally-chambered arch secured to the under side of the deck of a railway-car 20 and providing a flame-chamber, the side walls 25 of which are provided with glass-closed light-emitting apertures. Interposed between the flame-chamber and the deck of the car is a 30 ventilating-space which serves the double function of ventilating the car and of protecting the deck thereof from the heat generated by the apparatus.

The above objects are attained in the construction hereinafter described and which is 35 illustrated in the accompanying drawings, in which—

Figure 1 is a transverse section of the deck of a railway-car, illustrating the application of the invention thereto. Fig. 2 is a section 40 on the line 2 2 of Fig. 3. Fig. 3 is a section on the line 3 3 of Fig. 1. Fig. 4 is a view of the lamp looking from below, and Fig. 5 is a detail.

I have shown at 10 the arched deck of a 45 railway passenger-coach of ordinary construction. The illuminating apparatus which is herein claimed and described is designed to be mounted transversely of the car in the arch formed by the deck 10, a sufficient number 50 being provided and located at suitable inter-

vals to thoroughly illuminate the interior of the car.

The casing 11 of the apparatus consists of a chambered arch conforming to the contour of the deck of the car. Preferably this casing 11 is V-shaped in cross-section, as illustrated in the drawings, the upper edges of the sides 14 having vertical flanges 12, to which are secured angle-brackets 13 for fastening the casing to the deck 10. The sides 14 of 60 the casing are provided with light-emitting apertures which are closed by diaphanous plates 15, each of which is mounted in a hinged frame 16, the said frames being held when closed by spring-catches 17, engaging 65 wires 18, secured to the inner face of the sides 14 of the casing. Access is had through the medium of these openings for the purpose of igniting and extinguishing the gas at the burners 19, each of said burners being provided with a cock 20, and gas is led to the burners by a pipe 21, located in the bottom of the chamber of the arch or casing 11. The products of combustion from the burning gas and the heat generated within the flame- 70 chamber are led therefrom to the atmosphere by flues 22, projecting through the car-deck, a flue being located over each burner 19. These flues may be secured, as shown, to a longitudinal partition 23, which divides the 75 chambered arch 11 into two compartments—viz., a lower or flame chamber and an upper or ventilating chamber. The latter chamber spaces the flame-chamber from the deck of the car, so as to prevent the deck from becoming 80 scorched or warped and also provides for the ventilation of the car, as will be hereinafter explained.

Concentric with and inclosing each of the flues 22 is a flue 24, also secured to the partition 23 and provided with lateral apertures 25, establishing communication between the ventilating-compartment of the casing and the atmosphere.

The flanges 12, by means of which the illuminating apparatus is secured to the deck of the car, are provided with openings 26, leading from the interior of the car to the chamber between the partition 23 and the car-deck. In addition to spacing the flame-chamber from 90 95 100

the car-deck and providing a chamber through which a current of air is constantly passing, so as to avoid injuring the deck, this construction also secures a proper ventilation of the 5 car, the warm air therein passing through the openings 26 into the ventilating-chamber, thence through the apertures 25 into the flue 24 and to the atmosphere.

For the purpose of ventilating the flame-chamber in order to keep it comparatively cool, as well as to supply air to support combustion, a series of apertures or induction-ports 30 are provided in the walls 14, and within the chamber and adjacent to these 15 walls are located tubes 28, each having two series of oppositely-disposed apertures 29 29^a, the apertures on opposite sides of the pipe being out of alinement, and one series of these apertures, as 29^a, being in register with or 20 covering the apertures 30, so that while air may freely enter through the latter apertures or ports and pass into the flame-chamber through the tubes no light will be transmitted.

The upper ends of each pair of smoke and 25 ventilating flues 22 24 are covered with a cap 32, which is surrounded by a deflecting-band 33, the upper end of the flue 22 being laterally apertured and space being left between the cap 32 and the flue 24 and the band 33 to 30 allow the free exit of vapors.

The apparatus provides for wide distribution of the illuminating agents, so that there is avoided any brilliant center of illumination. The light comes from above. Each 35 arch throws light toward both ends of the car, securing effective and pleasing illumination. The apparatus is simple in construction and compact in form, utilizing much less space than the lamps ordinarily used, and it is readily adaptable, with slight modification, to any 40 construction of railway-car. The arrangement is such that the flame-chamber is thoroughly ventilated, thereby making the apparatus especially valuable for burning acetylene gas, and in addition it combines means 45 for effectually ventilating the car.

If desired, the casing 11 may be ornamented by providing the bottom thereof with jewel-closed apertures 27.

50 While I have shown the diaphanous plates 15 as elliptical, I do not confine myself thereto, the shape and number of the same being immaterial.

The flues 22 from the flame-chamber projecting through the deck of the car, the heat 55 generated in the flame-chamber is conveyed to the atmosphere and not permitted to escape in the car, as is the case with the ordinary lamp. This is a matter of considerable 60 moment, especially in warm weather.

It may be found desirable to install the illuminating apparatus during the building of the car, it being, in effect, a part of the car construction. It will be obvious that this will 65 be no departure from the spirit of my invention.

I claim as my invention—

1. In combination with a railway-car having a deck, a chambered arch crossing the deck and having diaphanous sections in each 70 side face, and an illuminating agent within the chamber of the arch.

2. In combination with a railway-car having a deck, a chambered arch crossing the deck and having its side faces in part diaphanous, and an illuminating agent within the 75 chamber of the arch.

3. In combination with a railway-car having a deck, a chambered arch crossing the deck and having its side faces diaphanous in 80 part, a plurality of gas-burners within the chamber of the arch, means for leading gas to the several burners, and a smoke-flue leading through the car-deck from the arch-chamber.

4. In combination with a railway-car having a deck, a chambered arch crossing the deck and having its side faces diaphanous in part and being provided with air-ports opening from the interior of the car, a plurality of gas-burners within the chamber of the arch, 85 means for leading gas to the several burners, and a smoke-flue leading through the car-deck from the arch-chamber.

5. In combination with a railway-car having a deck, a plurality of chambered arches 90 crossing the deck and spaced apart, the side faces of the several arches being in part diaphanous, and an illuminating agent within the chamber of each arch.

6. In combination with a railway-car having a deck, a chambered arch crossing the deck and having diaphanous sections in each side face, an illuminating agent within the chamber of the arch, and a partition forming a space between the chambered arch and 100 the deck of the car.

7. In combination with a railway-car having a deck, a chambered arch crossing the deck, a partition dividing the said chamber into upper and lower compartments, and an 110 illuminating agent within the lower compartment the walls of which are in part diaphanous.

8. In an illuminating and ventilating device for railway-cars, a chambered arch constructed and arranged to fit transversely within the deck of a car, a partition dividing the arched chamber into an upper ventilating-compartment and a lower flame-compartment, both compartments having induction-ports, 115 a flue leading upwardly from the ventilating-compartment, and a flue leading from the flame-compartment through the ventilating-compartment flue.

9. In combination with a railway-car having a deck, a chambered arch crossing the deck and having its side walls in part diaphanous and being divided into a lower or flame compartment and an upper or ventilating compartment, both of such compartments 120 having induction-ports, a flue leading from the flame-compartment through the car-deck, 125

130

- a flue opening communication between the ventilating-compartment and the atmosphere, a tube secured within the flame-compartment and having non-registering apertures at opposite sides thereof, the apertures at one side of the tube registering with induction-ports in the walls of the flame-compartment, and an illuminating agent within the flame-compartment.
- 10 10. In combination with a railway-car having a deck, a chambered arch crossing the deck and having one of its walls in part diaphanous, and an illuminating agent within the chamber of the arch.
- 15 11. In combination with a railway-car having a deck, a chambered arch crossing the deck and having one of its walls diaphanous

in part, a gas-burner within the chamber of the arch, means for conducting gas to the burner, and a smoke-flue leading from the 20 arch-chamber.

12. In a lamp, in combination, a casing providing a flame-chamber and having draft-apertures, one of the walls of the casing being in part diaphanous, an illuminating agent 25 within the flame-chamber, and a tube secured to the casing and having non-registering apertures at opposite sides thereof, the apertures at one side of the tube registering with the draft-apertures.

WILLIAM S. HAMM.
